(57) **CLAIM**

The ornamental design for a mounting bracket, as shown and described.

DESCRIPTION

FIG. 1 is a perspective view of the mounting bracket of the present invention;

FIG. 2 is a perspective view thereof;

FIG. 3 is a top view thereof;

FIG. 4 is a front view thereof;

FIG. 5 is a right side thereof;

FIG. 6 is a rear view thereof;

FIG. 7 is a left side view thereof;

FIG. 8 is a bottom view thereof; and,

FIG. 9 is an exploded view thereof.

The broken lines in the drawing figures depict environment and form no part of the claimed design.
